UNITED STATES PATENT OFFICE.

MARC BIRKIGT, OF BOIS-COLOMBES, FRANCE.

EXPLOSION-ENGINE.

1,401,862.

Specification of Letters Patent. Patented Dec. 27, 1921.

Application filed January 8, 1916. Serial No. 71,085.

To all whom it may concern:

Be it known that I, MARC BIRKIGT, citizen of the Republic of Switzerland, residing at Bois-Colombes, Department of Seine, France, 5 have invented certain new and useful Improvements in Explosion-Engines, of which the following is a specification.

This invention relates to water cooled engines, particularly explosion engines and 10 has for its object the building of such engines more simply than hitherto.

The invention consists in providing engines with a removable cylinder cover which supports all the distribution or valve gear 15 parts and having flat surfaces adapted to be connected to corresponding flat surfaces of the cylinder while the water circulation chambers with which the cover is provided are independent of those which surround the 20 cylinder.

The invention further consists in other arrangements which will be more fully described in the following description, taken in conjunction with the accompanying drawings in which—

Figure 1 represents a longitudinal section through one half of a four-cylinder internal combustion engine embodying the present invention.

Fig. 1^a is an elevation, partly in section, of the other half of the engine shown in Fig. 1.

Fig. 2 represents a transverse section of the engine on the line 2—2 of Fig. 1, and

Fig. 3 represents a transverse section through the engine on the line 3—3 of Fig. 1.

Similar parts are designated by the same reference characters in the several views.

The cylinders of the engine are made, 40 preferably by casting the four cylinders *a* in one piece and by providing in the wall of each cylinder, a chamber *a*¹ to receive the cooling water. Instead of extending the cylinders beyond the plane in which is situated 45 the upper face of the pistons when they are at their highest point, so as to constitute by such an extension the explosion chamber, the wall of the cylinders is practically stopped at the level of the said plane. Thus the same 50 chamber *a*¹ is used for cooling water for all the cylinders and the said chamber is completely closed. The end *a*² of the cylinders is carefully planed or otherwise machined.

55 A part *b* forms the cover of the cylinders, and the said part is provided with a cham-

ber *b*¹ for the cooling water and a flat face *b*² having surfaces corresponding to the surface of the upper wall of the cylinders, which surfaces are carefully machined so as to enable the said cover *b* to fit accurately. Four recesses *b*³ are provided of such a shape and position that as soon as the cover is put in place on the cylinders, the said recesses come in line with the said cylinders, and constitute explosion chambers. These are also machined, so as to insure absolute identity of the various cylinders, a condition greatly favorable to satisfactory operation.

The combustion chambers *b*³ are elongated 70 longitudinally of the cylinder casting so that the walls of the elongated ends of adjacent combustion chambers are spaced closer together than are the walls of the unelongated portions of said combustion chambers from 75 the outer wall of the cooling chamber *b*¹. By so narrowing the space between the adjacent combustion chambers an increase in the velocity of the cooling fluid through said space is produced with a corresponding increase 80 in the cooling efficiency of said cooling medium at this point.

Openings *b*⁴ are provided in the cover of the said recesses and form seats for the inlet valves *c* and the exhaust valves *d*, and conduits *c*¹ and *d*¹ connect the said openings respectively to the inlet pipe and to the exhaust pipe.

Guides *e* are made for the valve spindles, and bearings *f* for the parts operating the 90 valve rods. These bearings support the cam shaft *f*¹ which drives directly and in accordance with Specification No. 35,382 filed in the same name on the 21st June 1915. These valve rods are provided with a means for adjusting their length.

In the wall of the cylinders are provided two openings terminating at the chamber for the cooling water, and in the wall of the cover are also provided two openings terminating at the chamber for the cooling water, two of the said openings enabling the chambers *a*¹ and *b*¹ to be connected together by a tube *g*, while the other two *g*¹ and *g*² are intended to connect the said chambers respectively to the admission and to the discharge conduit for the cooling water. It is only necessary after having fitted in the cover *b*, the whole of the valve gear, to secure the said cover in place on the cylinders by bolts 105 *h* which are made to pass right through sleeves *h*¹ in the chambers *a*¹ and *b*¹. The

2
said chambers are then connected together by a pipe, in order that the engine may work.

The method of fixing by bolts h in sleeves h^1 avoids any deformation of the walls of the cylinder. The explosion chambers provided in the said cover, are machined so that they are of greater length than the diameter of the corresponding cylinder, so that the wall 10 of the said cylinder forms a flange preventing the valves from falling into the cylinder. In the case of large cylinders with four valves, the explosion chamber has the cross-section of a square with rounded off corners 15 and with the sides slightly greater than the diameter of the cylinder.

Obviously, the invention is not limited to the construction described, but comprises any modifications within the scope of the claims, 20 particularly that in which the explosion chamber forms a part of the cylinder the removal of the cover facilitating the machining.

I claim as my invention:—

25 1. An explosion cylinder casting comprising an integral block having a plurality of inner cylindrical walls forming explosion cylinders and an outer spaced wall connected at its top and bottom to said cylindrical walls 30 forming a water jacket about said cylinders, said cylinder casting having a flat upper surface, a head casting having an upper wall provided with valve apertures arranged longitudinally thereof, inner side walls coöperating with said upper wall to form combustion chambers each surrounding a pair of 35 valve apertures and being elongated longi-

tudinally of the head casting, each inner side wall being symmetrically arranged in overlapping relation to said cylinders, a 40 lower wall having a flat under surface co-operating with the flat upper surface of said cylinder casting, said inner side walls being joined to said lower wall and an outer side wall joined to said lower wall and surrounding said inner side walls the distance between the elongated ends of adjacent combustion chambers being less than the distance between the unelongated sides of said combustion chambers and said outer wall. 45

50 2. An explosion cylinder casting comprising an inner cylindrical wall forming a cylinder and an outer spaced wall connected at its top and bottom to said cylindrical wall by end walls, forming a water jacket about 55 said cylinder, said casting having a flat upper surface, a head casting having a flat lower surface coöperating with the flat upper surface of the cylinder casting, sleeves connected to the upper and lower end walls 60 of the cylinder water jacket and spaced from the inner and outer walls thereof and hollow threaded bosses within the head casting in registry with said sleeves when the head casting is in position and bolts passing into 65 said sleeves from the lower ends thereof and threadedly engaging in said hollow bosses.

In testimony whereof I have hereunto set my hand in presence of a subscribing witness.

MARC BIRKIGT.
